UNITED STATES PATENT OFFICE.

CLARENCE GARFIELD YORAN, OF MANCHESTER, IOWA.

ORDNANCE.

1,112,748.

Specification of Letters Patent.

Patented Oct. 6, 1914.

Application filed February 2, 1914. Serial No. 816,016.

To all whom it may concern:

Be it known that I, CLARENCE GARFIELD YORAN, a citizen of the United States, residing at Manchester, in the county of Delaware and State of Iowa, have invented certain new and useful Improvements in Ordnance; and I do declare the following to be a full, clear, and exact description of the invention, such as will enable others skilled in the art to which it appertains to make and use the same.

This invention relates to improvements in ordnance and more particularly to mountings therefor.

15 The primary object of the invention is to provide a device of this character employing a plurality of fire arms carried by a self-propelled vehicle and having means whereby they may be simultaneously fired and simultaneously adjusted to a lower or higher range.

A secondary object is to construct the mountings of the fire arms in such a manner as to render them readily removable for any 25 necessary purpose.

With the above objects in view, the invention resides in certain novel features of construction and combination herein described and claimed and shown in the drawings 30 wherein:

Figure 1 is a side elevation of the invention, parts being broken away and in section; Fig. 2 is a plan view of the forward portion of the parts shown in Fig. 1; Fig. 3 is a transverse section on line 3—3 of Fig. 35 1; Fig. 4 is a similar view on the line 4—4 of Fig. 2; and Fig. 5 is a detail vertical section on the line 5—5 of Fig. 2.

In the accompanying drawings, I have 40 shown an automobile A which is preferably of all metal construction for obvious reasons and is provided with a surrounding wall W which is provided with a door D at each side of the machine. Within the wall W is 45 a suitable seat S, steering wheel w and the various levers and pedals necessary for controlling the operating machinery of the car. The front portion 1 of the wall W is provided with a plurality of spaced upright 50 slots 2 which are disposed in horizontal alinement with similar slots 3 formed in an inclined shield 4 which is secured at its upper end to the portion 1 of the wall W and at its lower end to the hood H of the 55 car. Projecting loosely through the slots 2

and 3, are a plurality of barrels 5 of guns 6, the latter being supported as hereinafter described.

Rigidly supported by the side walls of the car is a transversely disposed horizontal shaft 7 which carries a plurality of spaced supporting plates 8 which are pivotally mounted thereon in any suitable manner as by forming eyes 9 on their lower ends and loosely mounting said eyes on the shaft 7. 60 Screws 10 having operating wheels 11 are passed loosely through the plates 8 and are threaded into the stocks of the guns 6, thereby pivotally mounting said guns on the shaft 7. 65

The portions of the guns 6 directly in rear of the upright portion 1 of the wall W are supported by means of screws 12 which are revolvably mounted in bearings 13 carried by the floor of the car, their threaded portions 70 being engaged with threaded sockets formed within the supporting blocks 14, to the opposite sides of which are pivoted ears 15 which are hingedly connected as at 16 to curved clamping arms 17 which are adapted 75 to embrace the sides of the guns 6 and be secured in position thereon by means of bolts 18 which are pivotally connected at 19 to one of said arms 17 while their free ends are threaded and passed removably through 80 notches 20 formed in the upper ends of the other arms 17, hand wheels 21 being threaded on the outer ends of said bolts and being adapted to draw the upper ends of the arms 17 toward each other when turned in the 85 proper direction.

Supported beneath the guns 6, is a transverse, horizontally disposed shaft 22 which is revolvably mounted in bearings formed on the lower ends of links 23 which depend 90 from the shaft 7 and are pivotally mounted thereon. The shaft 22 is further supported by clamps 24 which are substantially the same construction as the clamps previously described and an extended description thereof is not thought to be necessary. The shaft 22 is provided with a plurality of radially projecting fingers 25 which are adapted to be brought in contact with the triggers 26 of the guns 6 when said shaft is rotated in 95 any suitable manner as by a hand wheel 27, the fingers 25 being disposed in alinement so as to simultaneously trip the triggers of all of the guns.

From the above described mounting of 100

the guns 6 upon the shaft 7, it will be clearly seen that they are allowed a limited vertical movement within the slots 2 and 3, the screws 12 being employed for the purpose 5 of effecting said movement and said screws being simultaneously rotated by means of worms 28 carried by a revolubly supported shaft 29 and meshing with worm gears 30, one of which is disposed on each screw 12. 10 The shaft 29 is preferably provided with a hand wheel 31 for rotating it for the above mentioned purpose.

In order to more effectually shield the operator whose station is within the car A, I 15 provide each one of the guns 6 with a circular shield 32 which is removably secured to its barrel forward of the slots 3 in the inclined shield 4, and with an arcuate shield 33 which is pivotally connected to the longitudinal sides of the wall W and is supported in any desired position by means of links 34 which are pivoted to said shield and pass between screws 35 and said longitudinal walls, the screws being revolubly mounted 25 in suitable brackets and provided with operating handles.

From the above described construction and arrangement of parts, it will be seen that by rotating the wheel 27, the fingers 25 30 will contact with the triggers 26 of the guns 6 and will simultaneously fire them and that when it is desired to raise or lower the barrels of said guns, the hand wheel 31 may be rotated in the proper direction to effect this 35 movement. During any raising or lowering of the guns, it will be readily seen that the shaft 22 and fingers 25 will assume their same relation relative to the triggers 26, this being due to the suspension of said shaft 22 40 from the stocks of said guns.

By proper manipulation of my improved ordnance, a clean sweep might easily be made of the enemies' lines, since the entire vehicle carrying the guns may be turned 45 from side to side to vary the horizontal range of said guns.

By the specific mounting of the guns 6, any one of them may be readily removed for any necessary purpose, such as cleaning or 50 the substitution of a new fire arm.

By mounting the shield 33 in the above described manner, it may be lowered when the entire machine is being propelled, thus allowing a clearer view for the operator 55 thereof.

Although I have described my invention with considerable minuteness, I do not wish to be limited to details other than those amplified in the appended claims. Neither do 60 I wish to be limited to the application of the invention to a vehicle, since it is appar-

ent that it would operate to equal advantage on any appropriate form of support.

Having thus described my invention, what I claim as new and desire to secure by Letters Patent is:

1. An ordnance comprising an apertured shield, a transverse shaft in rear of said shield, a plurality of guns pivotally supported on said shaft to swing in a vertical plane and having their barrels projecting through the apertures in said shield, supporting brackets depending from said guns and carrying bearings, a trigger operating shaft revolubly mounted in said bearings 75 and carrying trigger tripping elements, means whereby said guns may be simultaneously rocked around their pivots and means whereby said trigger operating shaft may be rotated. 80

2. An ordnance comprising an apertured shield, a transverse shaft in rear of said shield, a plurality of guns pivotally supported on said shaft to swing in a vertical plane and having their barrels projecting 85 through the apertures in said shield, supporting brackets depending from said guns and said shaft and carrying bearings, a trigger operating shaft revolubly mounted in said bearings and carrying trigger tripping elements, means whereby said guns may be simultaneously rocked around their pivots 90 and means whereby said trigger operating shaft may be rotated.

3. An ordnance comprising an apertured shield, a horizontal shaft in rear of said shield, a plurality of spaced supporting plates pivoted to said shaft, a plurality of vertically adjustable supports forward of said shaft and in rear of said shield, a clamp 100 on each of said supports, a plurality of links depending from said shaft and carrying bearings, clamps rising from said bearings, a plurality of guns removably held within the clamps on said supports and said bearings and removably secured to said supporting plates at their rear ends, a trigger operating shaft revolubly mounted in said bearings, trigger tripping fingers on said shaft, means whereby the latter may be rotated and means for effecting the vertical adjustment of said supports simultaneously, 110 the barrels of said guns projecting loosely through the apertures in said shield.

In testimony whereof I have hereunto set 115 my hand in presence of two subscribing witnesses.

CLARENCE GARFIELD YORAN.
